CURRENT SUPPLY MEANS

Fritz Schröter, Berlin, Germany, assignor to Tele-funkens Gesellschaft fur Drahtlose Telegraphie m. b. H., Berlin, Germany, a corporation of Germany

Application July 18, 1929, Serial No. 379,168, and in Germany July 27, 1928

4 Claims. (Cl. 250—27)

In large power transmitter tubes especially of the kind in which the outside wall of the tubes consists wholly or partly of metal, the problem of maintaining a constant vacuum is attended with practical difficulties whenever the vacuum pump is not to be operated constantly. An impairment of the vacuum is liable to lead to "puncture", and this in turn may lead to destruction of the transmitter tube by the short-circuit current which starts to flow when such "break-down" happens.

To prevent such an occurrence, attempts have been made to limit the value of the short-circuit current to a permissible value. The breaking down of the tube itself may be accepted, since this will not occasion any substantial impairment of operations, indeed, it may result in an improvement of the vacuum in the tube.

If the plate potential of the transmitter tube is derived from an alternating current supply network by means of rectification by valves, the desired end may be insured by underheating (subnormal heating) of the valves whereby the thermionic current and thereby the short-circuit current are limited. However, such underheating of the valves involves the disadvantage that the potential fall of the valve under normal operating conditions and consequently the plate load are increased, and this tends to reduce the life of the valves.

Another means to limit the short-circuit current consists in inserting protective resistances in series with the tube, separate resistance being suitably provided in series with each tube in case a plurality of tubes are parallel connected. This scheme, however, is very costly since the protective resistance for the plates must be designed so as to be able to stand a large load, they are subject to high potential actions, and the overall efficiency of the equipment is diminished.

Now, according to the present invention a limitation of the short-circuit current is insured by that the magnetron effect is used for the valves, control of the magnetron effect being secured by the plate current itself by that the magnetron coil is connected directly in the path of the plate current. The size of this coil should most suitably be regulable in order that fine regulation of current limitation may be feasible, and that the magnetron effect may be caused to become operative in accordance with the use of a certain valve type in transmitters of different power.

Two practical applications of the invention have been illustrated in Figures 1 and 2.

Referring to Figure 1, S is a thermionic tube

of the triode type having an anode 2, cathode 4, and control grid electrode 6. The electrodes 2, 4 and 6 may be connected in alternating current circuits of any type, not shown, by way of leads 1, 3 and 5. Direct current potential for the plate 60 cathode circuit of this tube is supplied from a source 8. The source 8 may be of any type which supplies current, as, for example, alternating current, or rectified alternating current which needs smoothing and/or limiting. In the present case 65 it is assumed to be alternating current which is rectified by the thermionic tube V, which has its anode and cathode impedance connected in series between the anode 2 and cathode 4 by way of a magnetron winding W. The thermionic tube V 70 is located co-axially with respect to the winding W and within the field of the winding W, as shown.

The magnetron coil in the case of valves with water-cooled plates should preferably be disposed 75 around the metallic plate.

To increase the action it is advantageous to insert a capacity between the valve plate and the magnetron coil, as shown in Figure 2, said capacity, and, if desired, also the magnetron coil itself 80 consisting of part of the low-pass (choke) filter provided for the purpose of eliminating overtones or ripples from the plate direct current potential.

Arrangements, of course, could also be so made that the magnetron coil controlling the thermionic current is connected above the smoothing filter.

I claim:

1. Means for deriving unidirectional current of a controlled intensity from an alternating current source comprising, a rectifier having a hot electrode and a cold electrode, means for connecting said electrodes with said source, and means for limiting the amount of current passed by said rectifier comprising a winding in series in said connection, said rectifier being located in the field of said winding, the rectifier and the winding being co-axial so that the elements of the rectifier are symmetrically located in the field of said winding. 95

2. Means for producing unidirectional current from a source of alternating current and supplying a constant amount of such current to a load circuit comprising, a source of alternating current, an inductance, a thermionic rectifier co-axially mounted within said inductance so that the elements thereof are in the field of said inductance, and means for connecting said alternating current source, said load, said rectifier, and said inductance in series, whereby changes in the current 100 105 110

drawn from said alternating current source by said load will produce corresponding changes in the field of said inductance in which said rectifier is located and tend to maintain a constant flow of current through said rectifier.

3. Signalling apparatus comprising, a thermionic tube having anode, cathode and control grid electrode, said electrodes being adapted to be connected in alternating current signalling circuits, and means for supplying uni-directional current to the anode of said tube and for limiting the

amount supplied thereto comprising, a source of anode current, a thermionic device connected between said source and said anode, a winding in said connection, said winding and said device being co-axial with respect to each other, the electrodes of said device being located within the field of said winding.

4. An arrangement as claimed in claim 3 in which a capacity is connected in shunt with said winding.
